UNITED STATES PATENT OFFICE.

WILLIAM MCLENNAN, OF OGDENSBURG, NEW YORK.

INVALID-BED.

SPECIFICATION forming part of Letters Patent No. 739,336, dated September 22, 1903.

Application filed March 17, 1902. Serial No. 98,507. (No model.)

To all whom it may concern:

Be it known that I, WILLIAM MCLENNAN, a citizen of the United States, residing at Ogdensburg, in the county of St. Lawrence and 5 State of New York, have invented certain new and useful Improvements in Invalids' Beds; and I do hereby declare the following to be a full, clear, and exact description of the invention, such as will enable others skilled in the 10 art to which it appertains to make and use the same.

This invention relates to certain new and useful improvements in invalid-beds, and has for its object a device of this character 15 which shall embrace novel means whereby the occupant may be raised to a sitting posture or any degree of inclination desired in a gradual manner under the control of the operator and supported when the position desired 20 has been reached.

With the above and other objects in view the invention further resides in the novel details of construction and combination of parts to be hereinafter fully described and then set 25 forth in the claims.

Referring to the accompanying drawings, forming a part of this application, and in which like characters of reference indicate similar parts throughout the several views, 30 Figure 1 is a perspective view of my improved device. Fig. 2 is a side elevation of the means for operating the head-frame and the inclosing casing therefor, the latter being shown in section. Fig. 3 is a like view showing the manner of supporting the rack-bars 35 in position. Fig. 4 is a detail view of the head-frame, partly broken away. Fig. 5 is a detail view in section, showing the joint between the elements 8 and 9.

The bed 1 is preferably one of the well-known types of metal bedsteads, supporting the woven-wire mattress.

In order to more conveniently permit of transportation or facilitate the handling of 45 the bed, the head thereof is usually formed in two sections hinged one to the other, as at 2, the upper section carrying dogs 3, adapted for engagement with the lower section, whereby the former is secured in its extended position. The head-frame has a movable connection with the side rails of the bed by means of the socket 6, into which extends the

slip-rod 7, having a limited vertical movement. 8 designates a socket pivotally carried by the rod 7 and in which is revolubly mounted the rod 9, carrying a ratchet-wheel 10, engaged by the pawl 11, secured to the cross-bar 12, forming a component part of the head-frame. This cross-bar is also secured to the other of the rods on the farther side of 60 the bed, forming the head-frame or back-support. In order to provide a suitable supporting medium for the mattress of the head-frame, I employ a canvas apron 14, which is rigidly secured to the several aforesaid rods 65 and whose tension may be regulated at will by rotation of the rod 9, the latter being secured against rearward movement by the pawl previously mentioned.

It is a desideratum that the patient be submitted to as little jar, shock, or decided change in assuming a sitting posture from a lying one as is possible and that the same be effected in a gradual and minute manner, which I accomplish by novel means comprising rack-bars 15, having a hinge connection with the sockets 38, carried by the head-frame, and which extend into casings 16, suitably secured to the side rails of the bed. Intermeshing with the teeth of the rack-bar and mounted 80 within this casing is a pinion 17, which carries a pinion 18, preferably of a larger diameter. A pair of these pinions are secured to each end of a common shaft which extends in a direction transverse to the bed, assuring 85 their simultaneous action and the head-frame being evenly operated. In order to cause the racks to mesh with the pinions at all times, I mount cheek-pieces 19 loosely upon the common shaft and provide them with antifriction-rollers 20, engaging the rear of the rack-bar. A train of gears preferably having differential diameters intermesh with the pinion 18, the larger of the train of gears carrying operating means, such as a crank 21, whereby the 95 gears may be actuated to impart movement to the rack-bar. A spring-detent 22 has a pivotal mount within the casing and when in its normal position engages the driving-gear and secures the same against rearward, 100 movement.

Inasmuch as certain details of construction and combination of parts have been found necessary to a complete disclosure of the in-

vention, still I do not wish to limit myself to the exact construction shown and described, as it is obvious various changes may be made without departing from the spirit and scope 5 of my invention.

Having thus fully described my invention, what I claim as new, and desire to secure by Letters Patent, is—

1. In a device of the type set forth, the combination with the bed or the like, of rods carrying means at their lower ends for pivotally connecting the rods to the side rails of the bed, said means having a limited upward movement, means connected to the rods for raising and lowering the same, a connecting medium between the rods forming a support for the back-rest mattress, the latter operating independently of the bed-body mattress.

2. In a device of the type set forth, the combination with the bed or like, of a head-frame having a pivotal connection with the side rails of the bed, with means for permitting the pivotal connection to operate in a limited upward direction, the head-frame operating independent of the bed-body, and means for raising and lowering the head-frame.

3. In a device of the type set forth, the combination with a bed or the like, of a socket secured to each of the side rails of the bed and

having a slip-rod therein, a socket pivoted to the slip-rod, a rod mounted in the said last-named socket, a bar connecting the said last-named rods, and an apron secured to the last-named rod, with means for adjusting the tension of said apron, raising-bars carried by the rods last named, means for raising and lowering said bars, and means for locking said bars at several positions, substantially as described.

4. In a device of the type set forth, the combination with the bed or the like, of a socket secured to each of the side rails of the bed and having a slip-rod therein, with means for limiting the vertical movement of the slip-rod, a socket pivoted to the slip-rod, a rod mounted in the socket with a connection between the rods, means for raising and lowering said rods, said rods and said connection therebetween forming a support for the back-rest mattress, said back-rest mattress operating independently of the bed-body mattress.

In testimony whereof I affix my signature in presence of two witnesses.

WILLIAM McLENNAN.
